A. LAWSON,
BOOK SHEET PERFORATING DEVICE,
APPLICATION FILED JULY 10, 1908.

918,871.

Patented Apr. 20, 1909.

UNITED STATES PATENT OFFICE.

ALBERT LAWSON, OF ST. LOUIS, MISSOURI.

BOOK-SHEET-PERFORATING DEVICE.

No. 918,871.

Specification of Letters Patent.

Patented April 20, 1909.

Application filed July 10, 1908. Serial No. 442,898.

To all whom it may concern:

Be it known that I, ALBERT LAWSON, a citizen of the United States of America, residing in the city of St. Louis and State of Missouri, have invented certain new and useful Improvements in Book-Sheet-Perforating Devices, of which the following is a full, clear, and exact description, reference being had to the accompanying drawings, forming 10 part of this specification.

My invention relates to a device for use in perforating loose sheets of paper preparatory to binding them to books and the invention has for its object to facilitate the binding of loose sheets by affording means whereby the sheets may be readily and accurately assembled and held while being drilled or otherwise perforated previous to being bound together into a book.

20 Figure I is a perspective view of my device with a plurality of sheets of paper in position to be perforated. Fig. II is an enlarged plan view of the device with parts broken out. Fig. III is an enlarged view of the forward 25 portion of the device with the upper part in elevation and the lower parts in vertical section taken on line III—III, Fig. II. Fig. IV is an enlarged vertical section taken on line IV—IV, Fig. II.

30 In the accompanying drawings: 1 designates the table of my device, the rear end of which is supported by a foot piece 2 that serves to hold this portion of the table elevated.

35 3 is a support beneath the forward portion of the table and which preferably consists of an angle shaped bar, one flange of which is vertically disposed and the other flange of which is horizontally positioned beneath and attached to the table. The horizontal flange of this support is cut centrally of its ends, thereby permitting of the vertical flange being bent, as seen in dotted lines, Fig. II, in order that the central portion of 40 the support will be located rearwardly relative to the forward edge of the table while the outer ends of the support occupy positions nearer to the forward end of the table to more efficiently sustain the front end of 50 the table when the device is in use.

45 4 designates a pair of screw-threaded posts having slotted lower ends and which are fitted and fastened to the vertical flanges of the support 3 near its outer ends. The posts 4 55 may extend to any desired degree above the table 1.

5 are hand wheels having downwardly extending sleeves 6 which are screw-threaded internally to operate upon the screw-threaded posts 4. The sleeve of each hand wheel 60 is provided with an annular groove 7.

8 designates a jig bar provided at intervals between its ends with perforations 9 in which a boring tool or punch may be operated. Near each end of the jig bar is a slot 65 10 that extends inwardly from one side of the bar and is of sufficient dimensions to receive the reduced portion of the adjacent hand wheel sleeve 6 at the location of the groove 7 therein and to provide for the rotation of the sleeve in the jig bar.

11 are keys removably seated in the jig bar and extending across the slots therein to serve as keepers for the jig bar after it has been fitted to the hand wheel sleeve.

75 12 is an inverted U-shaped guide carried by the jig bar and provided with perforations 13 in which the boring implement utilized for sheet perforating operation may operate while it is being operated through the perforations in the jig bar.

14 is the practical use of my device, the sheets of paper to be perforated are held upon the table of the device against the gage 14 located at one side of the table 85 and so that the ends of the sheets which are to be perforated will occupy positions above openings 1^a at the forward end of the table and beneath the jig bar, it being understood that at this time the jig bar is in an elevated 90 position. After the desired number of sheets have been placed upon the table, the hand wheels 5 are operated upon the posts 4 with the result of causing their sleeves to turn in the slots of the jig bar and lower said jig 95 bar onto the sheets. The sheets therefore become clamped beneath the jig bar and any suitable implement, such as a boring bit, may be passed through the perforations in the guide 12 and the jig bar and then 100 through the sheets to perforate them, the implement finally passing into the holes 1^a in the table.

105 It will be seen that due to the construction and manner of attachment of the jig bar to the sleeves of the hand wheels by which it is operated, said bar may be readily detached from the hand wheels and removed from the remainder of the device when there is any necessity for such action and also 110 that either end of the jig bar may be detached without detaching the other, thereby

permitting of the bar being swung laterally with the sleeve of the other hand wheel serving as a pivotal member therefor.

I claim:

- 5 1. In a sheet perforating device, a table, screw-threaded posts extending above said table, hand wheels fitted to said posts and provided with sleeves, and a jig bar loosely fitted to said sleeves and adapted to be raised and lowered thereby during the movement of the hand wheels, substantially as set forth.
- 10 2. In a sheet perforating device, a table, screw-threaded posts extending above said table, hand wheels fitted to said posts and provided with sleeves, a jig bar loosely fitted to said sleeves and adapted to be raised and lowered thereby during the movement of the hand wheels, and a perforated implement 15 guide surmounting said jig bar, substantially as set forth.
- 20 3. In a sheet perforating device, a table, screw-threaded posts extending above said table, hand wheels fitted to said posts and having sleeves provided with annular grooves, and a jig bar fitted to said sleeves at the 25

locations of their grooves, substantially as set forth.

4. In a sheet perforating device, a table, screw-threaded posts extending above said table, hand wheels fitted to said posts and provided with sleeves having annular grooves, a jig bar provided with slots adapted to receive said sleeves at the locations of their grooves, and means for holding 30 35 said jig bar to said sleeves, substantially as set forth.

5. In a sheet perforating device, a table, a support for said table, screw threaded posts secured to said support and extending 40 above the table, hand wheels fitted to said posts and provided with sleeves having annular grooves, a jig bar provided with slots adapted to be fitted to said sleeves at the locations of the grooves therein, and keys 45 seated in said jig bar and extending across their slots to hold the jig bar to said sleeve, substantially as set forth.

ALBERT LAWSON.

In the presence of—

H. G. COOK,
BLANCHE HOGAN.
